UNITED STATES PATENT OFFICE.

RICHARD LESTER WILCOX, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

DIE-HOLDING MECHANISM.

Application filed May 19, 1924. Serial No. 714,527.

To all whom it may concern:

Be it known that I, RICHARD LESTER WILCOX, a citizen of the United States, residing at Waterbury, in the county of New Haven and State of Connecticut, have invented certain new and useful Improvements in Die-Holding Mechanisms, of which the following is a specification, reference being had therein to the accompanying drawings.

10 This invention relates to new and improved die holding mechanism for dies of a heading, upsetting machine or the like, although not limited to such use.

15 It is the object of this invention, among other things, to provide a mechanism of this character that is not limited to dies of a single size but may be utilized to hold dies of various sizes in operative relation to each other, thereby materially increasing the 20 capacity of a single machine. To these and other ends, my invention consists in the die holding mechanism having certain details of construction and combinations of parts as will be hereinafter described and more particularly pointed out in the claims.

25 Referring to the drawings in which like numerals of reference designate like parts in the several figures,

Figure 1 is a plan view of my improved mechanism shown in operative relation with a header or upsetting machine or the like;

Figure 2 is a transverse sectional view thereof taken generally upon line 2—2 of Figure 1;

30 Figure 3 is a detail perspective view of the fulcrum stud, washer and nut;

Figure 4 is a front elevation of my improved die holding mechanism with some of the adjacent parts of the machine with 40 which it is associated shown in section;

Figures 5, 6, and 7 are fragmentary elevations thereof showing different arrangements of some of the parts;

Figure 8 is a fragmentary plan view of 45 a portion of my improved mechanism illustrating a modified form of clamping device; and

Figure 9 is a sectional elevation thereof taken generally upon line 9—9 of Figure 8.

50 In heading, upsetting machines or the like, the dies are movably mounted and are substantially square in cross section.

Heretofore these machines have been constructed for a single size die, therefore it

has been the practice to have a separate machine for each size of die.

This objection has been partially met by an effort to make the dies of a uniform size and shape. This plan does not fully meet all conditions, particularly does it fail where a user has a number of dies of varying sizes that are still serviceable and for other reasons cannot and ought not to be made of any other size. The dies are made of special steel with great precision as to dimensions and are hardened and ground with much skill and labor. The improved mechanism herein shown and described, with a minimum adjustment of parts, is adapted for use with dies of various sizes. For the purpose of illustration only, I have shown my device as associated with a heading or upsetting machine, a portion of the body of which is designated in the drawing by the numeral 10.

This type of machine, as is usual, has a pocket in a portion of the bed within which the dies and associated mechanisms are operable. In the rear of this pocket is secured a backing plate 11, having a slot 12, in its upper edge, within which is adjustably mounted a fulcrum stud 13, having a head portion 14 with an opening 15 therethrough a threaded shank portion 16, and a rectangular subhead portion 17, which is substantially the same width as slot 12, and within which it is slidably mounted, being held against rotation by reason of its angular cross section. This fulcrum stud is held in any of its adjusted positions by the nut 18, and washer 19.

The dies 20, two in number are supported upon the bottom plate 21, which may or may not rest upon a packing plate 22, as may be necessary or convenient. Between the rear face of the dies 20, and the front of the backing plate 11, are the usual blocks and plates 23 that may be of any conventional form or shape, and constitute no part of the present invention. Through these blocks and plates 23, is an opening or aperture 24, which registers with an opening 25, in the quill 26, through which the wire rod is fed to the dies and held therebetween in any two of the notches 27 when in register with each other.

The dies are held against upward movement by a cap or cover 28, which is pro-

vided with rearwardly extending lugs 29, between which is the head 14 of the fulcrum stud 13, and connected therewith by the pin 30 that projects through said lugs and the opening 15 in the fulcrum stud. In the several figures this cap or cover is shown in its down position with the underside thereof in contact with the upper faces of the dies 20, and is there held by means of the clamps 31, against relative movement so as to permit a sliding movement of the dies between the bottom plate 21 and the cap 28. The form of cap or cover herein shown is provided with laterally projecting side portions 32, one of which rests upon the fixed plate 33, and the other upon the fixed part 34. The clamps 31 are adjustably secured to the bed 10 by the screws 35 that pass through elongated slots 36 whereby the clamps may be moved to fully uncover the cap or cover 28 and permit it to swing upon its pivot mounting to its open or up position as shown by broken lines in Figure 2. For convenience in raising this cap or cover I have provided a fixed lift bar 37. Relative endwise movement of the dies is prevented by the plates 38 and 39, the former of which is secured to the bottom plate 21 and the latter to the cap or cover 28. As shown in Figures 1, 2 and 4 the parts are arranged for dies, now termed for convenience, as the standard size, which are readily accessible for replacement, adjustment, etc., by merely shifting the clamps 31, grasping the lift bar 37, and swinging the cap or cover to its up or open position. The dies are held in their operative position by equally simple operations, that is, by returning the cap or cover to its down position with its side portions 32 engaging the plate 33, and fixed part 34 and then moving the clamps to the position shown in Figures 1 and 4, and locking them against movement by the screws 35.

To adapt the mechanism for dies that are either larger or smaller in cross section than the standard size, as above mentioned, the top and bottom of the side portions 32 are removed, an equal amount to receive the filling plates 40, the thickness of which equals one half the difference between the cross sectional dimension of the standard die and the new die. If this new die is larger, a filling plate 40 is attached to the underside of the side portions 32, as shown in Figure 6, and a filling plate 22 under the bottom plate of similar thickness, is substituted for the one shown in Figures 2 and 4.

If the new die is smaller than the standard size die, then the filling plate 40 may be placed upon the top of the side portion 32 as shown in Figure 7 and a filling plate 22 of similar thickness substituted. To accommodate the required varying positions of the under face of the cap or cover 28, the position of the fulcrum stud is shifted relatively to the backing plate 11 as before described. The under side of the cap or cover may be thus moved within the required limits and the under face thereof is always parallel 70 with the top face of the bottom plate 21. These filling plates 40, and backing plates 22 may be made of any desired thickness, are preferably interchangeable, and secured to the cap or cover by screws 41. If desired, 75 filling plates may be secured to both the top and bottom of the side portions 32 as shown in Figure 5. The clamps may also be provided with adjusting screws 42, as shown in Figures 8 and 9, so that the ends thereof 80 may impinge against the top of the side portions 32 whereby the clamps may occupy a position substantially parallel with the top of the side portions 32, irrespective of whether filling plates are used or not. By 85 the use of filling plates 40, and 22, of varying thickness and variously placed in relation to the cap or cover, and within predetermined limits, dies of varying dimensions may be used in a single machine. These 90 plates are inexpensive and require little or no labor to either install or remove which is equally true of the change of the relative positions of the cap or cover.

Modifications and alterations in the detailed construction of the several parts of this invention may be made within the scope of the appended claims. 95

What I claim is:

1. Means for holding dies in heading or upsetting machines or the like, comprising a die supporting member, and a cap or cover arranged so that it may be moved toward and away from a position wherein one face thereof is substantially parallel with one face of the member, the cap being adjustably mounted to vary such parallel position to accommodate dies of various sizes. 100
2. Means for holding dies in heading or upsetting machines or the like, comprising a die supporting member; a cap or cover; and means for adjustably connecting the same relatively to the member, whereby its closure position may be varied. 110
3. Means for holding dies in heading or upsetting machines or the like, comprising a die supporting member; a cap or cover; means for pivotally connecting the cap or cover relatively to the dies; and means for varying the position of the pivot connection. 115
4. Means for holding dies in heading or upsetting machines or the like, comprising a die supporting member; an element movable in a slot in a fixed part and adjustably secured in its several positions; and a cap or cover pivotally connected with the element. 125
5. Means for holding dies in heading or upsetting machines or the like, comprising 130

- a die supporting member; a backing plate; an element adjustably connected with the backing plate toward and away from the die supporting member; and a cap or cover 5 pivotally connected with the element.
6. Means for holding dies in heading or upsetting machines or the like, comprising a die supporting member; a backing plate having a slot therethrough; a stud projecting through the slot and adjustably connected with the backing plate in any of its adjusted positions; and a cap or cover pivotally connected with the stud.
7. Means for holding dies in heading or upsetting machines or the like, comprising a die supporting member, and a cap or cover arranged so that it may be moved toward and away from a position wherein one face thereof is substantially parallel with one 10 face of the member, the cap being adjustably mounted to vary such parallel position to accommodate dies of various size, the requisite thickness of said member beneath the dies depending upon the relative position of 20 the cap or cover.
8. Means for holding dies in heading or upsetting machines or the like, comprising a die supporting member; a backing plate having a feed orifice therethrough; a cap 25 or cover arranged so that it may be moved toward and away from a position wherein one face thereof is substantially parallel with one face of the member, the cap being adjustably mounted to vary such parallel position to 35 accommodate dies of various sizes and the supporting face of the member and the die contacting face of the cap or cover, when in relative operative positions, being substantially equally distant from said orifice.
- 40 9. Means for holding dies in heading or upsetting machines or the like, comprising a die supporting member; a cap or cover arranged so that it may be moved toward and away from a position wherein one face thereof is substantially parallel with one face of the member, the cap being adjustably mounted to vary such parallel position to 45 accommodate dies of various sizes; and means for holding the cap or cover against movement in its down or closed position.
- 50 10. Means for holding dies in heading or upsetting machines or the like, comprising a die supporting member; a cap or cover arranged so that it may be moved toward and away from a position wherein one face thereof is substantially parallel with one face of the member, the cap being adjustably mounted to vary such parallel position to 55 accommodate dies of various sizes; and means for holding the cap or cover against movement in its down or closed position, comprising one or more clamp devices connected with an adjacent fixed part.
- 60 11. Means for holding dies in heading or upsetting machines or the like, comprising a die supporting member; a backing plate having a feed orifice therethrough; a cap or cover arranged so that it may be moved toward and away from a position wherein one face thereof is substantially parallel with one face of the member, the cap being adjustably mounted to vary such parallel position to 65 accommodate dies of various sizes; and means for holding the cap or cover against movement in its down or closed position, comprising one or more clamp devices connected with 70
- upsetting machines or the like, comprising a die supporting member; a backing plate having a feed orifice therethrough; a cap or cover arranged so that it may be moved toward and away from a position wherein one face thereof is substantially parallel with one face of the member, the cap being adjustably mounted to vary such parallel position to 75 accommodate dies of various sizes and the face of the member and that of the cap or cover, when in relative operative positions, being substantially equally distant from said orifice; and one or more plates separably secured to the cap or cover that limit the said parallel position of the cap or cover.
- 80 12. Means for holding dies in heading or upsetting machines or the like, comprising a die supporting member, and a cap or cover arranged so that it may be moved toward and away from a position wherein one face thereof is substantially parallel with one face of the member, such parallel position being variable to accommodate dies of various sizes, the cap or cover in said parallel 85 position contacting with relatively fixed parts.
- 90 13. Means for holding dies in heading or upsetting machines or the like, comprising a die supporting member; a cap or cover arranged so that it may be moved toward and away from a position wherein one face thereof is substantially parallel with one face of the member, the cap being adjustably mounted to vary such parallel position to 95 accommodate dies of various sizes; and one or more plates connected with the cap or cover and engaging fixed parts to limit such parallel position.
- 100 14. Means for holding dies in heading or upsetting machines or the like, comprising a die supporting member; a cap or cover arranged so that it may be moved toward and away from a position wherein one face thereof is substantially parallel with one face of the member, the cap being adjustably mounted to vary such parallel position to 105 accommodate dies of various sizes; one or more plates connected with the cap or cover and engaging fixed parts to limit such parallel position; and means connected with a fixed part for holding the cap or cover against movement in said parallel position.
- 110 15. Means for holding dies in heading or upsetting machines or the like, comprising a die supporting member; a cap or cover arranged so that it may be moved toward and away from a position wherein one face thereof is substantially parallel with one face of the member, the cap being adjustably mounted to vary such parallel position to 115 accommodate dies of various sizes; and means for holding the cap or cover against movement in its down or closed position, comprising one or more clamp devices connected with 120
- 125
- 130

an adjacent fixed part and having one or more adjustable members connected therewith.

16. Means for holding dies in heading or upsetting machines or the like, whereby the top and bottom thereof will be substantially equi-distant from a feed orifice, comprising a supporting member, the position of one face of which is dependent upon the size of
- 5 the die; a cap or cover arranged so as to
- 10 adjustably move relatively to the member

and so limited in such movement in one direction that one face thereof is substantially parallel with the said face of said member and the same distance from the feed orifice whereby dies of varying sizes may be held; and means for securing the cap or cover against movement in such position.

In testimony whereof, I have hereunto affixed my signature.

REED LESTER WILCOX.
